UNITED STATES PATENT OFFICE.

JACOB L. SNYDER, OF BOSTON, MASSACHUSETTS, ASSIGNOR TO THE COLUMBIA ICE CREAM HORN COMPANY, A CORPORATION OF MASSACHUSETTS.

DESIGN FOR AN ICE-CREAM CONE.

53,168.

Specification for Design.

Patented Apr. 1, 1919.

Application filed January 23, 1919. Serial No. 272,774. Term of patent 7 years.

To all whom it may concern:

Be it known that I, JACOB L. SNYDER, a citizen of the United States, residing at Boston, in the county of Suffolk and State of Massachusetts, have invented a new, original, and ornamental Design for an Ice-Cream Cone, of which the following is a specification, reference being had to the accompanying drawing, forming part thereof.

The drawing is a perspective view of an ice cream cone, illustrating my new design.

I claim:—

The ornamental design for an ice cream cone, as shown in the drawing.

JACOB L. SNYDER.
